UNITED STATES PATENT OFFICE

LEE J. BLACK, OF BEAUMONT, TEXAS

BRAKE

Application filed December 22, 1928. Serial No. 327,859.

This invention relates to brakes, and more particularly to equalized brake mechanism for use in conjunction with the draw works of rotary well drilling apparatus.

5 An important object of the invention is the provision in apparatus of this character of a mounting for the brake such that the brake is aligned with the draw works and properly positioned with relation thereto by 10 attachments to the same beams or supports upon which the draw works foundations are mounted and the brake apparatus is a unit and may be installed or shipped as such.

15 A further and more important object of the invention is to provide equalizer mechanism eliminating the danger of complete in-operation in event of breakage of one of the brake bands or its connections to the operating mechanism or in event of slackening of the 20 band to such a extent that a grip upon the drum cannot be secured without an impossibly excessive movement of the operating mechanism.

25 A still further object of the invention is to provide equalized brake mechanism for apparatus of this character which is so constructed that the drum is substantially completely embraced, thereby eliminating the waste braking surface present in all types 30 of braking apparatus of this character with which I am familiar.

35 A still further object of the invention is to provide a device of this character which may be very readily adjustable to compensate for wear and in which separation of the braking element from the drum, when the braking element is released, is insured and made uniform about the periphery of the drum.

40 These and other objects I attain by the construction shown in the accompanying drawings, wherein for the purpose of illustration is shown a preferred embodiment of my invention and wherein:—

45 Figure 1 is a fragmentary end elevation of the draw works of rotary well drilling apparatus showing brake mechanism constructed in accordance with my invention applied thereto, parts being shown in section and parts being broken away;

50 Figure 2 is a plan view of the brake mecha-

nism, the connections for the brake bands being illustrated in position at one end of the mechanism and the positions of the drum flanges being illustrated in dotted lines;

55 Figure 3 is a transverse sectional view illustrating the connections of the operating shaft and equalizer bar.

Figure 4 is a partial section on the line 4—4 of Figure 2.

60 Referring now more particularly to the drawings, the numeral 10 generally designates a floor beam or sill of a rotary rig and more particularly that sill to which the uprights 11 of the draw works, generally designated at 12, are secured. These draw works include a drum 13, the ends of which have 65 brake flanges 14 grooved, as at 15, for the reception of a brake band 16. The bands 16 must be simultaneously operated to engage the drum and it will, of course, be understood that due to differences in the finish of drum faces and other causes, the braking surface 17 of such bands will wear at different speeds, with the result that the bands must be adjusted or else improper braking action 70 will occur. To eliminate this adjustment, equalizer mechanisms have been provided, but such mechanisms are, in many instances, dangerous, in that should either the band or the connections of the mechanism to the band at one end of the drum break, the entire mechanism becomes inoperative, and there is 75 danger of the tools or other supported material falling and causing serious damage either within the well or upon the floor of the derrick.

80 In accordance with my invention, I provide a plate, generally designated at 18, extending longitudinally of the derrick floor 19 beneath the drum. This plate is provided at its opposite ends with flanges 20 adapted to engage and be secured to the same face of the sill 10 as the uprights 11, so that its transverse position with relation to the draw works may be 85 fixed by employing these flanges as gauges. 90 Bolts 21 or the like are employed to secure these flanges to the sill to maintain the plate in position after it has been properly longitudinally adjusted, as will hereinafter be 95 rendered obvious.

The plate, for reasons hereinafter explained, is formed in a main section 22 and auxiliary sections 23 bolted to the main section at the ends thereof, as indicated at 24, and bearing the flanges 20. At its opposite ends and at what might be termed its front edge, the plate is provided with pairs of bearings 25 receiving opposite ends of a longitudinally extending operating shaft 26. 5 This shaft is held against longitudinal movement by means of collars 27 or the like and at its center has secured thereto an arm 28, the outer end of which is furcate and has the arms 29 thereof bridged by a pivot pin 30. 10 One end of this shaft has an operating lever 31 corresponding to the ordinary brake lever of such apparatus.

Mounted upon the pin 30 is a link 32, the opposite end of which engages a horizontal pin 33 carried by a longitudinally extending equalizing bar 34. The connections of the link 32 to the pins 30, 33 are sufficiently loose to permit oscillation of the equalizing bar within the necessary limits. These bars, adjacent their ends, pass through eyes 35 constructed to prevent vertical elevation of the bar while permitting a limited shifting movement of the bar transversely of the plate. The extreme ends of the bar have rearwardly 20 directed apertured ears receiving horizontal pivot pins 36. Immediately rearwardly of the bearings 25 are pairs of spaced apertured ears 37 receiving the ends of securing and pivot pins 38 upon which are mounted brake band clips 39 to which the fixed ends of the bands 16 are secured. The opposite ends of the bands have clips 40 provided with lugs 41 having a bore 42 extending in the general direction of the band. Within these lugs are 25 rotatably mounted nuts 43 which project at the rear ends of the lugs and are squared, as at 44, for arrangement by a wrench.

Directed through the nuts are eye bolts 45, the eyes 46 of which are received by the pins 45, 36. Lock nuts 47 engage opposite ends of the nuts 44 to secure adjusted positions of the eye bolts and these eye bolts in their engagement with the pins 36 have sufficient play to admit of the oscillatory movements of the 30 equalizer bar 34. In installation of a device of this character, the main plate 22 is separated from the plates 23 and the clips 40 are disengaged from the eye bolts. The entire main plate 22 with the bands carried thereby 35 can then be inserted from the forward side of the draw works to proper position beneath the drum, when the plates 23 may be secured thereto and then the entire assemblage bolted in position. In securing this position, as 40 hereinbefore set forth, the transverse position is determined by the flanges 20 and the longitudinal position may very readily be determined by passing the bands about the drums in the grooves 15 thereof and connecting them to their respective eye bolts, so that

the assemblage is properly longitudinally positioned.

In operation of the device, a pull upon the lever 31 will be transmitted to the equalizer bar 34 and thereby to the movable ends of the 70 brake bands, shifting them toward the fixed ends thereof. In event the movement at either end is excessive, the bar 34 engaging the forward wall of the yoke 35 will provide a fixed pivot against which the link 22 may 75 shift the bar to insure tightening of the band which is still in an operative condition. Therefore, if either of these bands break, the other band is still effective.

In restoring the bands to their released 80 position, if either of the bands tend to stick, the bar 34 adjacent the opposite end thereof from that at which the bands sticks will engage the forward wall of the associated yoke, again providing a fixed pivot about which the 85 bar may be swung to insure release of the stuck band. In addition to performing the functions just described, these yokes serve to guide the bar in its movements and eliminate waste motion in the braking or releasing 90 operations.

In combination with structure of this character, I provide front and rearward band stops 48 and 49 which are associated with the fixed and movable ends of each brake band respectively. Each stop comprises an attaching bracket 50 and an arcuately curved portion 51 confronting the outer face of the band and through which are extended adjustable set or stop screws 52. In releasing movements of the band, the movable end of the band, during initial disengagement, will, of course, be first shifted outwardly and this shifting movement will result in its engagement by the set-screws 52 of the associated 100 curved portion 51. Its outward movement thus limited, a further movement of its clip will cause a disengaging movement further about the periphery of the drum. The supports extend to points approximately 120° 105 spaced about the bottom of the drum surface, with the result that the band, when in expanded condition, is squeezed between two braces, so that the upper portion thereof is held in properly spaced relation to the drum 110 and does not drag thereon. If, at any time, a band becomes worn to such an extent that an adjustment is necessary, this is readily 115 accomplished by simply rotating the nut 43 thereof.

Attention is directed to the fact that with a construction of this character, the adjacent ends of the bands closely approach one another, so that the waste or unused braking surface which, in most devices of this character, constitutes practically one-fourth of the available surface, is reduced substantially to a zero point.

Since the construction hereinbefore set forth is capable of a certain range of change 130

and modification without materially departing from the spirit of the invention, I do not limit myself to such specific structure except as hereinafter claimed.

5. I claim:

1. In equalized brake mechanism for the drums of rotary drilling draw works and the like, and in combination with a drum having brake flanges at its opposite ends, a supporting plate extending longitudinally of the drum and having its ends in close proximity to said flanges, means for securing the plate to a support, brake bands each secured at opposite ends of the plate and in alignment with the adjacent brake flange, a bar extending longitudinally and shiftable transversely of the plate, connections between the opposite ends of said bar and the opposite ends of said brake bands, and means mounted upon 10 said plate for shifting said bar transversely of the plate permitting pivotal movements of the bar, said plate having yokes through which opposite ends of the bar pass, said yokes each providing positive limits for 15 movement of the bar in either direction, each yoke providing a fulcrum against which the bar may rock in case of the breakage or loosening of one of the brake bands.

2. In equalized brake mechanism for the 20 drums of rotary drilling draw works and the like, and in combination with a drum having brake flanges at its opposite ends, a supporting plate extending longitudinally of the drum and having its ends in close proximity to said flanges, means for securing the plate to a support, brake bands, each extending over a drum flange and secured to the plate at one end, a bar extending longitudinally and shiftable transversely of the plate, connections between the opposite ends of said bar and the opposite ends of said brake bands, and means mounted upon the plate for shifting said bar transversely of the plate permitting pivotal movements of the bar, said 25 plate having yokes through which opposite ends of the bar pass, said yokes each providing positive stops limiting the movement of the bar in either direction and constituting fulcrums for said bar and said yokes preventing separation of the bar and plate.

3. In equalized brake mechanism for the 30 drums of rotary drilling draw works and the like, and in combination with a drum having brake flanges at its opposite ends, a plate extending longitudinally of the drum and having its ends in close proximity to said flanges, means for securing the plate to a support, aligned bearings at opposite ends of the plate, a rock shaft mounted therein, a brake band clip pivoted adjacent each bearing and adapted for connection to one end of a band encircling the associated flange, a bar shiftable upon the plate, bolts pivotally connected with opposite ends of the bar, brake 35 band clips adjustable longitudinally of said

bolts and adapted for engagement with the opposite ends of the brake bands, an arm secured to the shaft in alignment with the center of the bar, and a link connection between the bar and said arm permitting pivotal 70 movements of the bar in a plane paralleling the plate.

4. In equalized brake mechanism for the drums of rotary drilling draw works and the like, and in combination with a drum having 75 brake flanges at its opposite ends, a plate extending longitudinally of the drum and having its ends in close proximity to said flanges, means for securing the plate to a support, aligned bearings at opposite ends of the plate, a rock shaft mounted therein, a brake band clip pivoted adjacent each bearing and adapted for connection to one end of a band encircling the associated flange, a bar shiftable upon the plate, bolts pivotally connected with opposite ends of the bar, brake band clips adjustable longitudinally of said bolts and adapted for engagement with the opposite ends of the brake bands, an arm secured to the shaft in alignment with the center of the bar, a link connection between the bar and said arm permitting pivotal movements of the bar in a plane paralleling the plate, and means maintaining the bar in engagement with the plate.

5. In equalized brake mechanism for the drums of rotary drilling draw works and the like, and in combination with a drum having brake flanges at its opposite ends, a plate extending longitudinally of the drum and having its ends in close proximity to said flanges, means for securing the plate to a support, aligned bearings at opposite ends of the plate, a rock shaft mounted therein, a brake band clip pivoted adjacent each bearing and adapted for connection to one end of a band encircling the associated flange, a bar shiftable upon the plate, bolts pivotally connected with opposite ends of the bar, brake band clips adjustable longitudinally of said bolts and adapted for engagement with the opposite ends of the brake bands, an arm secured to the shaft in alignment with the center of the bar, a link connection between the bar and said arm permitting pivotal 100 movements of the bar in a plane paralleling the plate, and means maintaining the bar in engagement with the plate and limiting movement of opposite ends of the bar in either direction.

6. In equalized brake mechanism for the drums of rotary drilling draw works and the like, and in combination with a drum having brake flanges at its opposite ends, a plate extending longitudinally of the drum and having its ends in close proximity to said flanges, means for securing the plate to a support, aligned bearings at opposite ends of the plate, a rock shaft mounted therein, a brake band clip pivoted adjacent each bearing and adapt-

- ed for connection to one end of a band encircling the associated flange, a bar slidable upon the plate, bolts pivotally connected with opposite ends of the bar, brake band clips 5 adjustable longitudinally of said bolts and adapted for engagement with the opposite ends of the brake bands, an arm secured to the shaft in alignment with the center of the bar, a link connection between the bar and said arm permitting pivotal movements of the bar in a plane paralleling the plate, and yokes carried by the plate through which opposite ends of the bar are directed including portions limiting movement of the bar in 10 either direction.
7. In a draw works and in combination, a sill, a flooring supported from the sill, standards likewise supported from the sill, a drum supported from the standards in spaced relation to the flooring and having brake flanges at its opposite ends, a plate seated upon said flooring beneath the drum and having flanges engaging the sill to determine its transverse alignment with the drum, bands encircling 15 the flanges of the drum, means anchoring corresponding ends of the bands to the plates, and an equalizer bar and operating mechanism therefor carried by said plate and connected to opposite ends of the bands, said flanges being detachably connected with the plate and the equalizer bar being detachably connected with the last named ends of the bands whereby upon removal of said flanges and release of the last named ends of the 20 bands, the plate, bands and associated mechanism may be removed as a unit.
8. In a draw works, the combination of a drum having brake flanges at its opposite ends, brake bands engaging the brake flanges, means anchoring corresponding ends of said brake bands, an equalizing bar connected to the opposite ends of said brake bands, means for shifting said equalizing bar to tighten or 25 loosen the bands, and stops disposed inward of the ends of the bar acting to limit shifting movements of opposite ends of the bar in either direction and providing spaced fulcrums against which one or the other of the ends of the bar will bear in the event of 30 excessive looseness or breakage of one or the other of the bands.
9. In combination with a drum having brake flanges at its opposite ends, brake bands, means anchoring corresponding ends of said brake bands, an equalizer bar connected to the opposite ends of said brake bands, means connected to the equalizer bar 35 to shift it to thereby tighten or loosen the bands, and yokes disposed inward of the ends of the bands and through which the bar passes, said yokes limiting the forward and rearward movement of the bar and also acting as fulcrums in case one or the other of the brake bands becomes excessively loosened 40 or breaks.
10. In combination with a drum having brake flanges at its opposite ends, brake bands surrounding the flanges, means anchoring corresponding ends of said brake bands, an equalizer bar connected to the opposite ends of said brake bands, means for shifting the equalizer bar to tighten or loosen the bands, and elements limiting the rearward movement of the bar and disposed adjacent the ends thereof and against which the edge of the bar bears when the bar is fully retracted, said elements in case one or the other of the bands becomes loosened or breaks, acting as fulcrums as and for the purpose stated. 45
11. A brake band supporting unit for use with a drum having brake flanges and brake bands surrounding the flanges, the unit comprising a plate having a depending flange at its rear edge, the plate and flange being adapted to engage upon and against a sill, said plate having portions projecting in either direction and carrying bearings, a brake actuating shaft mounted upon said bearings, means mounted upon said plate adjacent said bearings for engaging one end of each of the brake bands, an equalizer bar disposed upon said plate, and having means whereby it may be operatively connected to the other end of each brake band, the shaft having an arm, a link connecting said arm to the equalizer bar, the plate having yokes extending over the bar and permitting a limited movement of the bar and holding the bar to the plate, members mounted at opposite ends of the plate beyond said brake band engaging means on the bar and plate, said members extending upwardly approximately concentric to the brake flanges and brake bands, said members having adjustable means extending through them for engaging the outer surfaces of the brake bands forward and rearward of the drum to thus support the brake bands in concentric relation to the brake flanges. 50
12. In a draw works, a drum having a brake flange, a band brake extending around said flange, the two ends of the brake being disposed substantially in alignment with each other beneath the drum, means for anchoring one end of the brake band, the free end of the brake band having an eye disposed in approximately horizontal alignment with said anchoring means, a brake lever having an arm, an operative connection between the arm and the eye including a bolt operatively engaged with the arm and extending through the eye and a nut on opposite ends of the eye and engaging said bolt whereby the free end of the brake band may be adjusted. 55
13. In a draw works, a drum, a brake flange, a brake band extending around the flange, a plate disposed beneath the drum, means for anchoring one end of the brake band to said plate, a shaft mounted upon the plate and having an arm, a link extending 60

from the arm and operatively connected to the free end of the brake band, and front and rear band stops associated with the fixed and movable ends of the brake band, said stops limiting the downward movement of the brake band with reference to the drum when the brake band is released to thus hold the upper portion of the brake band in spaced relation to the drum when the brake band is released.

10 In testimony whereof I affix my signature.
